UNITED STATES PATENT OFFICE.

WILLIAM RIECK AND EDISON E. RANDALL, OF KANKAKEE, ILLINOIS, ASSIGNEES TO
PARAMOUNT KNITTING COMPANY, OF CHICAGO, ILLINOIS, A CORPORATION OF
ILLINOIS.

MACHINE FOR SEWING LOOPED FABRICS.

1,107,704.

Specification of Letters Patent. Patented Aug. 18, 1914.

Application filed June 23, 1910. Serial No. 568,445.

To all whom it may concern:

Be it known that we, WILLIAM RIECK and EDISON E. RANDALL, citizens of the United States, and residents of Kankakee, county 5 of Kankakee, State of Illinois, have invented an Improvement in Machines for Sewing Looped Fabrics, of which the following description, in connection with the accompanying drawing, is a specification, like chartering drawing, 10 actors on the drawing representing like parts.

This invention relates to a machine for uniting or sewing together the edges of knitted goods or looped fabrics and as hereinafter illustrated is particularly designed for 15 sewing together edges of such articles as stockings, as when the stocking is knit on a circular knitting machine beginning at the toe, and the edges at the toe have to be united to complete the stocking. Machines 20 of this general type and of various forms are well known. In their general features they may be illustrated by reference to the patent to Henshall No. 589,723, dated September 7, 1897. Such a machine comprises 25 usually an intermittently rotating work-supporting ring carrying a circular series of radially projecting impaling pins, and stitch-forming mechanism, the needle of which operates over each impaling pin as 30 it comes beneath the needle. The edges of the knit or looped fabric to be united have their meshes superposed and placed on the impaling pins so that the needle passes 35 therethrough and the stitching unites the fabric.

The work-supporting ring is necessarily of considerable size and when the edges of small articles, such as stockings, are to be 40 united a number of stockings are hung upon the impaling pins by the operative. As fast as one stocking has been stitched and has passed the stitch-forming mechanism it is removed from the ring, either automatically 45 or by the operative, and a fresh stocking is placed upon the ring, the operative in the meantime cutting by hand the threads extending from the removed stocking to the preceding one. The operative in placing 50 the stockings upon the impaling pins is guided only by her eye and has to work very rapidly so that in practice the distance between the stockings as they are placed upon the ring varies greatly. Moreover, when the connecting threads are cut 55

by the operative they are cut very unevenly, frequently so close to one stocking as to allow the thread to ravel back and leave a hole and frequently so far from the other stocking as to leave too long ends 60 which not only wastes thread but is very uncomfortable to the foot of the wearer. The United States Government recognizes the importance of the length of the uniting thread by requiring in stockings furnished 65 for the Army that these ends shall not vary materially from one-fourth of an inch.

The present invention provides means for obviating all these difficulties, for securing uniformity and exactness in length of the 70 ends of the uniting threads, prevents unnecessary waste of thread, saves the time of the operative and so facilitates her work that the stockings may be more rapidly placed upon the ring. These results are 75 secured by arranging the impaling pins in series, each series containing the requisite number of pins to support one article, such as a stocking, spacing the series a definite distance apart, as, for example, one-half 80 inch, and providing an automatically-actuated cutter to sever the threads midway of the separating spaces.

The invention will appear more fully from the accompanying description and drawings 85 and will be particularly pointed out in the appended claims.

The drawings represent an ordinary form of machine for sewing looped fabrics such as illustrated in the beforementioned patent 90 with the present invention embodied therein in a preferred form.

In the drawings, Figure 1 is a top plan view of the machine; Fig. 2 is a detail elevation looking toward the cutting mechanism radially of the machine; Fig. 3 is a vertical cross section taken radially of the machine close to the cutting mechanism; Fig. 4 is a top plan view of the portion of the machine shown in Fig. 3. 100

It is unnecessary to describe in detail a machine for sewing looped fabrics of the type herein illustrated, so far as its general features are concerned, because it is well known. Suffice it to note that 1 represents a suitable base or support on which is mounted the main shaft 2 and from which extends the overhanging arm 3 carrying depending therefrom and rigid with respect thereto the plate or support 4 in which the 110

- ring 5 rotates. The plate 4 represents an annular groove in which the ring 5 is seated and the ring is held in place by the annulus 6 screwed to the plate.
- 5 The impaling pins 7 are of the usual form and are mounted on the ring 5 to project radially thereof. In the present invention these impaling pins are arranged in series or groups A, B, C, D, etc., each of which is of sufficient length or extent to hold the meshes of the edges of the given article, such as a stocking, which are to be united and which, therefore, constitutes what may be termed a fabric-supporting member. These series or groups are also spaced at fixed distances apart, as, for example, one-half inch, so that if a cutter operate midway therebetween the severed ends of the uniting threads will be always of the same desired length as, for example, one-fourth inch. The main shaft 2 operates the usual mechanisms in this type of machine. Through an eccentric 8 it operates trimmers 9 which trim off the edges of the knitted goods evenly as they approach the stitching point. An oscillating needle-carrying arm 10 and its needle 11 are shown operated from the shaft 2 and as each impaling pin 7 comes beneath the needle, the needle is actuated to pass over the pin through the meshes suspended thereon to stitch the edges together. After the work has passed the stitching point it passes beneath a rotary brush 12 driven from the shaft 2 and any threads, yarn, or fibers are brushed off. The impaling pin ring is given its intermittent or step-by-step movement usually by an annular rack 13 and suitable connections operated from an eccentric 14 on the shaft 2.
- 40 The cutting mechanism for severing the threads left by the stitch-forming mechanism extending between adjacent stockings is preferably located a short distance past the stitch-forming mechanism, as indicated in Fig. 1 and is shown in detail in the remaining figures of the drawing. It may be of any suitable construction but the form herein shown has been found very efficient and serves to illustrate a preferred embodiment of this feature of the invention. Co-operating brackets are secured to the plate 4, one 15 being attached to the upper surface of the plate, as by screws 16, to project outwardly and radially, and the other 17 being secured to the under surface of the plate as by the screws 18 and projecting outwardly beneath the first. The bracket 15 carries a cutter lever 20 pivoted at 21 thereon and guided in a slot in an upwardly projecting portion thereof. A vertical bar 22 is attached to the cutter lever and a spring 23 extending from the upper end thereof to the bracket 15 normally acts to depress the cutter lever and, consequently, the cutter knife 24 mounted near the end of the cutter lever. This bar 22 extends downwardly and is beveled at its lower end. The bracket 17 is provided with an edge to coöperate with the knife 24. A large guide 25 is secured to the bracket 15 by a bolt 19 to insure the passage of the work beneath the cutter. Depressions 26 are formed in the ring 5 beneath the bar 22 beveled at one side, and these depressions are so located that when each space between the series or groups of impaling pins comes beneath the cutter knife the bar 22 will be forced into the depression by the spring 23, thus actuating the cutter and severing the thread. The continued rotation of the ring causes the co-acting bevel surfaces on the bar and the depression to raise the bar until it slides along on the upper surface of the ring. The bar 22 is formed with a shoulder 27 so that the knife can be locked out of cutting position whenever desired by raising the bar until the shoulder catches on the upper surface of the bracket part 15 where it will then be held by the spring 23 until released.
- 45 The operation of the machine is apparent from the foregoing description. The operative stands about opposite the stitch-forming mechanism and places the stocking or other article on a group of impaling pins, one on each group. As the stockings pass in the rotation of the ring beneath the various mechanisms referred to the edges are trimmed, united by the stitch-forming mechanism, brushed, and finally the cutting mechanism severs the threads midway between successive groups of pins, thus leaving ends of exactly the required length, and then the stockings are removed from the pins. Thus waste of thread is prevented, danger from holes due to cutting too close to the knitted web eliminated, the discomfort from too long ends obviated, and the speed with which the work may be handled materially increased.
- 50 It will be observed that the cutting mechanism is automatically actuated to sever the threads left by the stitching mechanism substantially midway between successive stockings, and while in the form shown these stockings are supported by the impaling pins arranged in series or groups, each of which is of sufficient length or extent to hold the meshes of the edges of the stocking, yet the invention, so far as it relates to the cutting mechanism, is not to be limited to any particular means or manner of supporting the stockings, or other articles.
- 55 Having fully described our invention what we claim as new and desire to secure by Letters Patent is:
- 60 1. A machine for sewing looped fabrics comprising a ring support, a ring rotarily mounted thereon, groups of impaling pins arranged in an endless series on said ring with fixed spaces between said groups, a

- cutter lever carrying a cutting knife and pivoted to said support to allow the cutter to swing downwardly into said spaces, a spring to depress the cutter lever, a bar connected to said cutter lever to hold the same elevated when the end of the bar rests upon the surface of the ring, depressions in the ring coöordinated with the spaces, and means for intermittently rotating the ring where-
5 by when the middle of each space comes opposite the cutter knife the bar will drop into the corresponding depression allowing the actuation of the cutter to sever the thread extending across the space.
10 2. A machine for sewing looped fabrics comprising a ring support, a ring rotarily mounted thereon, groups of impaling pins projecting radially of said ring and ar- ranged with wide spaces between said
15 20 groups, cutting mechanism comprising a fixed member mounted on the ring support and projecting beneath the impaling pins and a movable member mounted on the sup- port and projecting over the impaling pins,

means for intermittently rotating the ring 25 to bring the spaces successively opposite to the cutting mechanism, and means for there- upon actuating the movable member of the cutting mechanism to sheer the thread ex-
30 tending across the space.

3. A machine for sewing looped fabrics comprising a ring support, cutting mecha- nism mounted thereon, a ring rotarily mounted thereon, impaling pins arranged on said ring, means automatically actuated in- dependent of the sewing mechanism upon the presentation of a space between suc-
35 ccessive stockings opposite said cutting mecha- nism to actuate the cutting mechanism to sever the thread extending across the space. 40

In testimony whereof, we have signed our names to this specification, in the presence of two subscribing witnesses.
